UNITED STATES PATENT OFFICE

2,442,363

WINDOW STRUCTURES

Earl P. Jones, Fort Lauderdale, Fla., assignor to
 Gate City Sash and Door Company, Fort
 Lauderdale, Fla., a corporation of Florida

Application May 8, 1944, Serial No. 534,572

7 Claims. (Cl. 20—53)

1

This invention relates to window structures, particularly of the so-called awning window type, and to mechanism for operating the same.

Among the objects of the present invention are to provide an awning type window and hardware construction designed so that it can be installed or removed from a window frame without having to remove substantially any of the surrounding members of the jamb or sill; to provide an awning type window wherein the window sashes are operated by a worm and gear construction that may be installed on either side of the window opening and which controls the operation of the sash on both sides thereof; to provide such a construction wherein the worm and gear actuator gives positive control at any angle of the opening, and in addition securely locks the window when completely closed, and without further locking attachments; to provide an awning type window including one or more individual sashes hingedly connected to the frame for a swinging movement to open or closed position wherein the axes of the hinges are constantly fixed so as to hold the topmost sash from swinging downwardly as it swings outwardly, in combination with means for preventing rain from blowing in over the top sash when said sash is moved to open position; to provide an awning type window composed of a vertical series of hinged sashes which are constructed and arranged to eliminate the need of transom bars, mullions, or fixed divisional members in the frame between the top and bottom walls of adjacent sashes; to provide a window of the awning type having a vertical tier of swingable sashes wherein the bottom member of the next higher sash is adapted to close directly upon and interfit with the top member of the next lower sash of a series; to provide an awning type window wherein the hardware is designed so that it can be practically stamped of sheet steel or any other type of sheet metal; to provide a construction of the foregoing character having sash arms which are designed for quick and simple installation and removal by inserting screws in the rear face of the sash, and likewise wherein the bracket members are connected to the actuating mechanism by means of a simple rivet and cotter pin construction; to provide an awning type window of the foregoing construction wherein the hardware is designed so that it can be operated without interference with screens, Venetian blinds, or draperies; to provide the operating mechanism with a readily removable handle which may be removed when the apparatus is to be installed in detention wards or mental hospitals, whereby no one can open or

2

close or disturb the open adjustment of the windows except when the handle is in place; to provide the foregoing construction wherein the hardware is completely exposed and easily accessible and is not concealed by jambs or sills, but on the contrary is partially concealed by means of the installation of a screen member installed at the rear of the awning type windows, the stile of which screen aids in partially concealing the operating hardware; to provide an awning type window construction which may be installed in the present type of window frame construction without the addition of special types of frame members and the like; to provide these and other objects of invention as will be apparent from a perusal of the following specification when taken in connection with the accompanying drawings, wherein:

Figure 1 is a perspective exterior view of one form of the awning type window showing the same installed in a building exterior.

Figure 2 is a vertical cross sectional view showing the awning type window as installed in a building exterior;

Figure 3 is a fragmentary outside view of the sash in closed position;

Figure 4 is a vertical section taken on the line 4—4 of Figure 5, wherein the multiple window sash is applied to a wooden exterior construction;

Figure 5 is a sectional view taken on the line 5—5 of Figure 4;

Figure 6 is a plan sectional view taken on the line 6—6 of Figure 4; and

Figures 7, 8, 9 and 10 are perspective views of sections of the different pieces of hardware that go to make up the mechanical operating means for the multiple sash.

Referring to Figure 1 there is shown in perspective view a portion of a building having a window structure embodying the present invention. This window structure is conveniently called an awning type window since the window is provided with a plurality of sashes 11, 12, 13, 14 arranged in tiers above each other so that when closed the upper sash rail and the lower sash rail of adjacent sashes are in abutment thus limiting the need for any mullions or other spacing bars. Figure 1 shows a window assembly having four sets of sashes 15, 16, 17, and 18 each comprising four sashes above each other which when opened in awning fashion appear as shown and have the advantage of permitting adequate air circulation since the awning effect deflects the air upward thus constantly moving the warm air normally accumulating at the ceiling with

other types of windows. An arrangement such as shown has the further advantage of permitting ventilation during rainy or inclement weather without danger of water damage to the interior sills or walls or floor area about the window opening. Furthermore the need and expense of large projecting eaves or similar structure has been eliminated.

Each of the sashes 11, 12, 13, and 14 is hingedly secured adjacent the top sash rail to the outer window casing. A suitable operating mechanism is mounted on the inside between the side jambs and the window sill so as to eliminate the need for any special expensive structures which would be the case where the operating mechanism is mounted within vertical side members or stiles. This manner of structure permits a window of this type to be inserted in the ordinary window opening without the necessity of a special type of structure as will subsequently become apparent.

From Figures 2 and 3 it will be seen that the upper window sash 11 is hingedly supported by a pair of hinges 19 secured by suitable screws to the top rail and side rail of the sash and to the adjacent outer casing of the window frame. Figure 2 particularly shows the manner in which the window may be used in a house of masonry construction. The sashes 11 to 14 are supported within a structure comprising a head jamb 21 which may be rabbeted at 22 to facilitate mounting a screen window without the use of special hardware, a sill 23 and interconnecting side jambs and side stops. Immediately above the upper sash rail of the sash 11 there is positioned a head blind 24 and a head jamb 25 arranged for cooperation with interlocking stepped configuration of the upper sash rail of the sash 11. The sill 23 is mounted in interlocking relation to a stiffener 26 against which is positioned a window stool 27 and the usual window apron 28. The head jamb 21 may be recessed sufficiently to receive the upper portion of a sash arm 29 secured to the upper sash 11. Each of the other sashes such as the sash 14 is also provided with a sash arm such as the sash arm 29-c. The various sash arms 29, 29-c which correspond to the arms attached to the sashes 11 and 14 are interconnected by a vertical link member 31. By suitable plates 32 secured by screws passing through the side stop and into the side jamb, there is supported a rock shaft 33 which carries at each end a crank arm 34 which is interconnected by a link 35 to the lowermost sash arm 29-c. The rock shaft 33 is provided at one end with a gear 36 which meshes with a worm gear 37 mounted on a shaft 38. An extension 40 of this shaft extends under the window stool 27 and through the apron 28. The end of the shaft 40 is provided with a handle or crank 39. Turning the crank 39 actuates the shafts 38 and 40 so as to cause the worm to turn and by engagement with the gear 36 move the rock shaft 33 through an angle so as to position the sashes 11 and 14 at any desired angle. Actuation of the rock shaft 33 will move the lever arm 34 in a counter-clockwise direction as seen in Figure 2 so as to exert a downward force on the ends of the sash arms 29 to 29-c thereby to move the sashes 11 to 14 toward the dotted line positions shown in Figure 2. The operating mechanism is readily accessible from the inside of the building and yet is hidden to a considerable degree by an inside window screen 41 the upper rail of which fits into the plowed or rabbeted recess 22 of the head jamb

21, and the bottom of which rests upon the stiffener 26 and is retained by the window stool 27. The side members of the screen 41 engage the side stops as subsequently will become apparent by reference to Figures 4 and 5.

By referring to Figures 4, 5, and 6, it will become apparent how a window structure of the type previously described is readily applied to a frame building. To simplify this disclosure

10 similar parts have been given similar reference characters even through some of the parts might vary slightly in dimensions. For example the head blind 24, the head casing 25, and the window stool 27 differ in dimension slightly from 15 corresponding parts shown in Figure 2. In Figure 2 the head casing 25 and the sill 23 were made weather tight by suitable caulking. In the frame house or building structure as shown in Figures 4, 5, and 6 the window sill 23 extends 20 beyond the siding of the house so as to adequately drain off rain and moisture from the window frame. From Figure 4 it will be seen that the head casing is protected by an outer casing strip 42 which overlaps the upper edge of the head 25 casing. On the outer casing 42 there may also be positioned a metal drip molding 43. To further protect the window structure the head casing is provided with a drip molding 44 to prevent 30 moisture from entering between the head casing 25 and the upper sash rail 45 of the sash 11. The drip molding 44 extends across the window between the pair of sash hinges 19. The lower sash rail 46 of the upper sash such as the sash 13 has a drip molding-like lower configuration and is 35 slanted outwardly so as to drain off any moisture which may have collected between the lower sash rail 46 of the sash 13 and the upper sash rail 47 of the adjacent sash such as the sash 14. The sill 24 of course has a configuration similar to the 40 configuration of the upper sash rail 47 so that the lower sash rail 48 of the sash 14 cooperates therewith to form a weather tight joint.

The window structure embodying the present invention has been shown as applied to a frame building structure of the type using bucks and 45 hence buck members 49 and 51 are shown in Figure 4 above the head jamb 21 and a lower buck member 52 is shown beneath the sill 23. In Figure 6 side buck members 53 and 54 are shown 50 adjacent the side jamb 55 in the upper portion of the drawing. The lower portion of the drawing shows another window set adjacent the window, and the two side jambs 55 and 55-a may be separated by bucks 56, or where no bucks are 55 used the member 56 will comprise a stud. The frame for the window includes side jambs 55 which have side stops 57 secured thereto. In the corner between the side stop 57 and the vertical blind stop 58, there is positioned a weather strip 60 packing cord 59 which is engaged by the inner corner of the vertical or side rail of each of the sashes. Adjacent the blind stop 58 is an exterior casing 61, and the joint between the exterior casing 61 and the buck member 62 is closed by an 65 exterior casing trim strip 63. The pairs of hinges 19-c are secured in position by suitable screws which extend through the exterior casing member 61 into the blind stop 58, and by screws extending into the side sash rails 64 of the sash 14. 70 On the inside of the window as is apparent from Figures 5 and 6, the upper sash 11 is provided with a sash arm 29 secured by screws extending into the upper sash rail 45 and the side sash rail 65. Similarly the sash arm 29-c 75 is secured by screws extending into the upper

sash rail 66 and the side sash rail 65. The support plates 32 provided at each side of the window engage the side stops 57 and are secured by screws extending therethrough into the side jambs 55. The lower portion of the plate 32 is provided with bosses or bearing members 67 which serve to support the shaft 38 upon which the worm gear 37 is mounted. The shafts 38 and 40 extend through the apron 28 which may be provided with a suitable escutcheon 68.

The various details of the hardware are further illustrated in Figures 7 to 10. From Figure 7 it will be seen that the plate 32 which is provided adjacent its lower edge with the bearing-like bosses 67 has suitable apertures 69 for the insertion of the fastening screws. In the central portion of the member 32 there is an aperture or opening 71 which is adapted to support the end of the rock shaft 33.

The operating shaft and crank shown in Figure 8 are mounted within the bosses 67 of the member 32 shown in Figure 7 and the worm gear 37 is interposed between the two bosses 67. A suitable interconnecting collar 72 is mounted on the end shaft 38 adjacent the front boss 67 of the mounting plate 32. The crank 39 is provided with a suitable hand grip or knob 73. The crank 39 is secured to the shaft extension 40, which has a hexagonal cross section, in any suitable manner as by riveting. A suitable knob 73 is positioned at the end of the crank arm 39. The interconnecting member 72 mounted on the end of the shaft 38 is secured to that shaft by a set screw 74. The other end of the member 72 is provided with a hexagonal opening 75 for receiving the hexagonal shaft extension 40. Where it is desired to have the handle 39 permanently secured in position a set screw 76 may be tightened to bear against the shaft extension 40. Where, for example in institutions, it is desired to remove the handle so that the patients or inmates may not adjust the windows the set screw 76 need not be used and the handle 39 may be carried from window to window and inserted through the escutcheon 68 to engage the hexagonal opening 75 in the connecting member 72. Each of the hinges 19 comprises two complementary portions 78 and 79 provided with suitable holes 81 for receiving fastening screws. Each of the members 78 and 79 is provided with upstanding wing-like portions 82 and 83 each having an aperture therein for receiving a rivet. A washer is interposed between members 82 and 83 and the members are then riveted together to form a hinge.

Each of the sashes is provided at the inside with a pair of sash arms, one half of a pair being shown in Figure 10. The sash arm 29 therefore has a mounting plate portion 84 provided with suitable apertures 85 for the fastening screws. The end of the arm 29 is provided with an aperture 86 for receiving a cotter key retained bolt or fastening member 87 shown in Figure 5.

From the foregoing disclosure of the hardware utilized for opening and closing the window sashes, it will be seen that the majority of the parts may be made of stampings thus eliminating the high cost of machined gears and casings. The sash arms are readily installed by the use of ordinary screws and interconnected with the remaining hardware by simple rivets or bolts held in position with a cotter key while the hardware is completely exposed and readily accessible so as to be easily inspected and repaired if necessary. The hardware can readily be installed or

removed without disturbing any of the surrounding wood work. Each of the sashes is mounted on two hinges located closely adjacent the upper sash rail so that the sashes pivot substantially

- 5 from their upper edge and do not move downwardly while moving outwardly as is the case in other types of windows which necessarily require a different and more expensive type of hinge. The sash arms are arranged in pairs and the 10 rock shaft extends between the side stops of the window frame. The worm gear and outriding gear may be positioned on either side of the window and positively control the operation and position of each of the sashes. Operation of the 15 hardware does not interfere with screens, Venetian blinds, or draperies and yet is not unsightly because the screen partially conceals the hardware from view.

Windows of the type shown and described may 20 be combined with fixed side light windows which produce a harmonious architectural design and a combination of a window of this type together with a side light on either side will cost no more than the equivalent size of the common type of double hung mullion window.

While for the purpose of illustrating and describing the present invention, certain specific embodiments of a preferred type have been disclosed in the drawing, it is to be understood that 30 the invention is not to be limited thereby since obviously such variations are contemplated as may be commensurate with the spirit and scope of the invention as defined in the appended claims.

35 This invention is claimed as follows:

1. A window comprising a plurality of window sashes arranged so that the upper and lower rails of adjacent sashes are in abutment, a frame for said sashes, means hingedly supporting each sash from the exterior of said frame in close proximity to the upper rail of the sash, and operating means for simultaneously opening and closing said window sashes comprising a rock shaft extending above the sill of the frame between the 40 side jambs, a pair of sash arms secured to opposite side rails of each sash, and removable linkage levers interconnecting the sash arms with each side to said rock shaft.

2. A window comprising a plurality of window 50 sashes arranged in a plane one above the other so that the upper and lower rails of adjacent sashes are in abutment, a frame for said sashes, means hingedly supporting each sash from the exterior of said frame in close proximity to the upper rail of the sash, and operating means for simultaneously opening and closing said window sashes, comprising means secured to each of the side jambs immediately above the sill and supporting a rock shaft extending above the sill between

55 the side jambs on said frame, a pair of sash arms secured to opposite side rails of each sash, and removable link levers interconnecting the sash arms on each side to said rock shaft.

3. A window comprising a plurality of window 60 sashes arranged in a plane one above the other so that the upper and lower rails of adjacent sashes are in abutment, a frame for said sashes, means hingedly supporting each sash from said frame in close proximity to the upper rail of the sash, a 65 stool and a depending apron and operating means for simultaneously opening and closing said window sashes, comprising means secured to the side jambs immediately above the sill and supporting a rock shaft extending above the sill between the 70 side jamb of said frame, a pair of sash arms se-

cured to opposite side rails of each sash, linkage levers interconnecting the sash arms on each side to said rock shaft, said levers being supported solely by said sash arms in the proximity of the side jambs, a gear mounted on said rock shaft, a cooperating worm gear mounted on a shaft extending beneath the window stool, through the apron and above the sill, and a crank arranged for operating said worm gear.

4. A window comprising a plurality of window sashes arranged in a plane one above the other so that the upper and lower rails of adjacent sashes are in abutment, a frame for said sashes, a stool and an apron cooperating with said frame, means hingedly supporting each sash from said frame in close proximity to the upper rail of the sash, and operating means for simultaneously opening and closing said window sashes, comprising means secured to the side jambs immediately above the sill and supporting a rock shaft extending above the sill between the side jambs on said frame, a pair of sash arms secured to opposite side rails of each sash, linkage levers interconnecting said sash arms by pins and cotter keys, said linkage levers being supported solely by said sash arms adjacent said side jambs and being connected to said rock shaft, a gear mounted on said rock shaft, and means including a worm gear cooperating with said gear on said rock shaft and mounted upon a shaft positioned above the sill and extending beneath the stool and beyond the apron of said window for actuating said rock shaft said worm gear shaft being supported by one of said rock shaft supporting means.

5. The combination for a window having sashes arranged when closed one above the other with the upper and lower rails of adjacent sashes in direct abutment in a frame formed of head and side jambs, a sill and exterior casing members, comprising means for hingedly supporting each sash from said exterior casing members in close proximity to the upper rail of the sash, a pair of sash arms for each sash adapted to be secured on the inside of the window to opposite side rails of the sash, a rock shaft adapted to be mounted immediately above the sill between the side jambs of the window, a pair of support plates for said rock shaft, link levers interconnecting the sash arms on each side of the window to said rock shaft, said levers being supported solely by said sash arms closely adjacent the exterior of said side jambs and means carried by one of said support plates for moving said rock shaft a selected amount.

6. The combination for a window having sashes arranged when closed one above the other with the upper and lower rails of adjacent sashes in direct abutment in a frame formed of head and side jambs, a sill and exterior casing members, 60

comprising a pair of forwardly extending hinges for each sash for supporting the sash from the exterior casing members in close proximity to the upper rail of the sash, a pair of sash arms for each sash adapted to be secured on the inside of the sash to opposite side rails, a pair of support plates adapted to be secured on opposite sides of said sash, a rock shaft adapted to be supported between the side jambs of the window above the sill thereof by said pair of support plates, a plurality of link members each pivotally interconnected with said sash arms and arranged to be actuated by said rock shaft, said link arms being freely supported from said sash arms adjacent said side jambs and means for adjusting said rock shaft to a selected position for determining the position of the sashes relative to the frame including a gear mounted on said rock shaft and a worm gear carried by one of said support plates.

10 7. The combination for a window having sashes arranged when closed one above the other with the upper and lower rails of adjacent sashes in direct abutment in a frame formed of head and side jambs, a sill and exterior casing members, 25 comprising a pair of forwardly extending hinges for each sash for supporting the sash from the exterior casing member of the window in close proximity to the upper rails of the sash, a pair of sash arms for each sash adapted to be secured on the other side of the sash to opposite side rails adjacent the exterior of said side jambs, a rock shaft adapted to be mounted above the window sill between the side jambs, a pair of lever arms mounted on said rock shaft and located adjacent the ends thereof exteriorly of said side jambs, a plurality of link levers interconnecting the sash arms on each side of the sash to the lever arm on the rock shaft, said linkage levers being secured to said lever arm and to said sash arms by removable pin members, and worm and gear means for moving said rock shaft to a desired adjusted position simultaneously for determining the position of each of said sashes relative to the window frame.
